(57) **CLAIM**

The ornamental design for a display tray, as shown and described.

DESCRIPTION

FIG. 1 is a top, end, and side perspective view of a display tray, showing our new design with a shallow base portion; FIG. 2 is a bottom, end, and side perspective view thereof; FIG. 3 is a right side elevational view thereof, where the left side elevational view is a mirror image of the right side; FIG. 4 is a front elevational view thereof, where the rear elevational view is a mirror image of the front side; FIG. 5 is a bottom plan view thereof; and FIG. 6 is a top plan view thereof.

FIG. 7 is a top, end, and side perspective view of a display tray, showing our new design with a deep base portion; FIG. 8 is a bottom, end, and side perspective view thereof; FIG. 9 is a right side elevational view thereof, where the left side elevational view is a mirror image of the right side; FIG. 10 is a front elevational view thereof, where the rear elevational view is a mirror image of the front side; FIG. 11 is a bottom plan view thereof; and, FIG. 12 is a top plan view thereof.
